UNITED STATES PATENT OFFICE.

ELEUTHERE PAUL DU PONT, OF WILMINGTON, DELAWARE.

MEANS FOR INSURING THE SAFE MANIPULATION OF EXPLOSIVES.

1,240,548.

Specification of Letters Patent. Patented Sept. 18, 1917.

Application filed March 23, 1917. Serial No. 157,060.

To all whom it may concern:

Be it known that I, ELEUTHERE PAUL DU PONT, a citizen of the United States, residing at Wilmington, county of New Castle, 5 and State of Delaware, have invented a new and useful Improvement in Means for Insuring the Safe Manipulation of Explosives, of which the following is a full, clear, and exact description, reference being had 10 to the accompanying drawings, which form a part of this specification.

The ordinary practice in operations such as loading primers, wrapping fuses, etc., which require but a small amount of explosive for each individual operation, is to supply each operative with enough explosive to carry on a large number of operations successively, such supply being from time to time renewed. The finished product is allowed to accumulate and is removed periodically. 20

The supply of explosive and accumulated finished product is of necessity considerable and is sufficient to be a source of great 25 danger to the operatives, in case of explosion or fire.

The object of my invention is to so dispose the supplies of explosive and the finished product, in all such operations as 30 require a number of successive similar operations involving small quantities of explosive for each operation, so that any explosion thereof will be relatively harmless, and to protect the operative from explosion or 35 burning of any explosive other than such relatively small quantity as he may be using in a very few individual operations; at the same time providing means whereby the supplies of explosive shall be readily obtainable by the operative and the finished product readily disposed of. 40

To this end my invention consists in placing an explosion proof partition or barricade between the bench at which the operations are carried on and both the source of 45 supply of explosive and the point where the finished product accumulates pending its removal to storage or elsewhere.

My invention also consists in the means 50 for supplying the explosive to the operative and removing the finished product.

Referring to the drawings, in which like letters refer to similar parts in all the figures:

55 Figure 1 is a cross sectional view of a

building with safety partition and means for supplying powder pellets for the purpose of wrapping them in paper to form fuses and removing the finished product and a chute for the disposal of defective material. 60

Fig. 2 is a front view of the chute leading to a defective product container.

Fig. 3 is a plan view of an explosive supply container. 65

Fig. 4 is a cross sectional view of a building with safety partition and supply containers and finished product containers for use in placing gauze cups on the ends of wrapped fuses. 70

Fig. 5 is a plan view of container for rolled unfinished fuses.

Fig. 6 is a plan view of a container for the fuses after being finished.

Fig. 7 is a side view in section of Fig. 6. 75
The partition *a*, of sufficient strength to stand a predetermined explosive force, is erected in the rectangular building *b*, one of the sides of the building opposite the partition *a* being preferably left open. On one 80 side of the partition is suitably fastened the work bench *c*. On the other side of the partition are suitably fastened the explosive container *d*, the finished product container *e*, and the defective material container *e*. 85

The explosive container, open at the top, is formed of sheet metal having the contracted neck forming the lip *f* which extends through a suitable aperture in the partition of the size of the neck, and on a level 90 with the top of the bench. The rear of the container being at a higher level than the neck permits the explosive to run into the lip when the pan is shaken.

The finished product is placed in the 95 finished product container *g*, one end of which extends through the partition through a suitable aperture therein, in a position convenient to the hand of the operative. 100

The explosive and finished product containers are located on the side of the partition facing the open side of the building, the work bench being on the side of the partition facing the closed side of the building. 105

In practice the explosive container is filled by an operative who passes along the walk way *m*. The operative on the opposite side of the partition obtains explosive as it is 110

required and only in such quantities as is required for an individual operation, or for a very few operations, through the contracted neck of the explosive container.

5 As each individual operation is finished the finished product is placed in the finished product container *l* and is carried by gravity through the partition and is deposited at the rear of the container.

10 The container *e'*, on the opposite side of the partition from the operative, is adapted to receive any material found to be defective. Defective material is passed into the container *e'* by means of the triangular chute *e* 15 which passes through suitable apertures in the partition and bench.

The operative is only placed in danger from the explosive of such small quantity of explosive as he is using in the conduct of a 20 single operation, for example, the loading of a single primer, or the wrapping or finishing of a single fuse.

The force of an explosion of the explosive supply, of the finished product, or of any 25 defective material, will be spent against the partition, and will not in any way tend to injure the operative, the partition being built of a strength to withstand an explosion of the entire supply of explosive and 30 finished product. The containers being open at the top and the side of the building being open, free escape is afforded for the explosive force and without danger of destroying the partition.

35 A modification may be made in the above described apparatus, for use in finishing the ends of wrapped fuses. The fuse container *j*, formed of sheet metal, is open at the top and is trough shaped. The lower corner 40 protrudes through the partition above the level of the bench. A portion of said corner is cut out at *k*. The operative withdraws the fuses, one at a time, through the cut out corner as he requires them. The rear of the 45 fuse container is slightly raised to permit the fuses to roll to the front and register with the cut out corner.

The container *l* for the wrapped fuses is formed with flaring sides, the narrow end 50 extending through the partition far enough for the admission of a fuse horizontally. The fuses roll down the bottom of the container and accumulate at the wide end.

I prefer to cover the bottom of the container with felt, while the sides are of metal; the friction between the fuse and the felt, together with the smooth flaring sides prevent the fuse from turning in its travel 55 along the bottom of the container.

60 It is of course necessary to have a person to replenish the supplies of explosives in the supply containers and to remove the finished product.

I do not limit my invention to the specific 65 types of apparatus herein described except

as defined in the appended claims, as my invention is capable of modification to meet the requirements of any type of operation requiring successive supplies of explosives, whether carried out manually or by machinery.

Having now fully described my invention what I claim and desire to protect by Letters Patent is:

1. Means for protecting operatives performing operations involving the successive manipulation of small quantities of explosives, comprising a barricade, and an explosive supply container extending through an aperture in the barricade whereby the supply of explosive material on one side of the barricade may pass by small instalments to the operative on the other side of the barricade.

2. Means for protecting operatives performing operations involving the successive manipulation of small quantities of explosives, comprising a barricade, and a finished product container extending through an aperture in the barricade whereby the units of the product as provided by the operator on one side of the barricade may be successively disposed of and accumulate on the other side of the barricade.

3. Means for protecting operatives performing operations involving the successive manipulation of small quantities of explosives, comprising a barricade, an explosive supply container on one side of the barricade, said barricade having an aperture communicating with said container and providing an inlet for the passage to the operator on the other side of the barricade of successive instalments of the explosive supply.

4. Means for protecting operatives performing operations involving the successive manipulation of small quantities of explosives, comprising a barricade, a finished product container on one side of the barricade, said barricade having an aperture communicating with said container and providing an outlet for the passage from the operator on the other side of the barricade of successive units of the finished product.

5. Means for protecting operatives successively manipulating small quantities of explosives in the successive formation of numerous units of finished or partly finished product, comprising a barricade, an explosive supply container and a finished product container on one side of the barricade; said barricade having an aperture communicating with the explosive supply container and providing an inlet for the passage to the operator on the other side of the barricade of successive instalments of the explosive supply and an aperture communicating with the finished product container and providing an outlet for the passage from the operator of successive units of the finished product.

6. Means for protecting operatives engaged in successive manipulation of small quantities of explosives, comprising a barricade, a work table on one side of the barricade, an explosive supply container on the opposite side of the barricade above the level of the work table and communicating with the first named side of the barricade through an aperture, and a finished product container 10 on the same side of the barricade as the explosive supply container and below the level of the work table and communicating with the first named side of the barricade through another aperture.
- 15 7. The combination with an explosive proof partition, of an explosive supply container and a finished product container on one side of said partition, and means to deliver explosive to and receive finished product from the opposite side of said partition.
- 20 8. The combination with a work table, of an explosive supply container and a finished product container and an explosive proof partition separating said table from said containers, there being restricted openings in said partition permitting communication between said table and said containers.
- 25 9. The combination with an explosion proof partition, of an explosive container fastened to said partition and having a contracted neck adapted to extend through said partition for the delivery of explosive material to the opposite side thereof, and a finished product container having communica-
- tion through said partition and adapted to receive the finished product.
10. The combination with a barricade containing a suitable aperture, of a device on which operations may be performed upon articles containing explosives, a pan to contain powder, a lip on the end of the pan projecting through the barricade into which powder may be caused to flow from the body of the pan by shaking the pan, said pan being set on a slight incline to insure delivery into the lip.
- 15 11. The combination with a barricade having a suitable aperture, of a finished product container having a restricted end extending through an aperture in the barricade, the bottom of said container being inclined to slope away from said restricted end to cause articles containing explosives placed in the restricted end of the container to roll or slide to the far end of said container and there accumulate.
- 20 12. The combination with a barricade containing a suitable aperture, of a device on which operations may be performed on articles containing explosives, and a waste chute extending through the said barricade whereby defective explosives may be carried into a suitable container.
- 25 In testimony of which invention, I have hereunto set my hand, at Philadelphia, Pa., on this 21st day of March, 1917.

ELEUTHERE PAUL DU PONT.
